UNITED STATES PATENT OFFICE.

ANTON I. SANDBO, OF ROCK ISLAND, ILLINOIS, ASSIGNOR TO THE NORTH DAKOTA GAS ENGINE MANUFACTURING COMPANY, OF LANGSFORD, NORTH DAKOTA, A CORPORATION OF NORTH DAKOTA.

INTERNAL-COMBUSTION ENGINE.

1,143,649.

Specification of Letters Patent. Patented June 22, 1915.

Application filed April 18, 1914. Serial No. 832,276.

To all whom it may concern:

Be it known that I, ANTON I. SANDBO, a citizen of the United States, residing at 4522 Sixth avenue, Rock Island, in the county of Rock Island and State of Illinois, have invented certain new and useful Improvements in Internal-Combustion Engines; and I do hereby declare the following to be a full, clear, and exact description of the invention, such as will enable others skilled in the art to which it appertains to make and use the same.

This invention is in the nature of an internal combustion engine and the primary object of the invention is to provide an improved engine of this class which will be possessed of certain advantages in the way of simplicity of construction, ease of operation, ready adjustment, and non-liability of disarrangement or breakage of parts under ordinary usage.

A further improvement embodied in my invention is to locate all parts which need adjustment from time to time in positions readily accessible from the outside.

With the object of generally improving the construction of the engine in order to carry out the expressed objects, my invention consists in the improved construction arrangement and combination of parts which will be hereinafter fully described and afterward specifically claimed.

In order that the construction and operation thereof may be readily comprehended, I have illustrated an approved embodiment of my invention in the accompanying drawings, and I will now proceed to specifically describe said construction and operation, having reference to said drawings, in which:

Figure 1 represents a view of the engine in side elevation with one of the cylinders and pistons in vertical central section, Fig. 2, a detail view showing the contacts of the igniter in side elevation, Fig. 3, a detail view showing the main gear with the spring contact wheel thereon, Fig. 4, a detail view in top plan of the carbureter and its ports, for connecting with the two cylinders. Fig. 5, a detail view of a portion of the pitman showing the shaft in section, Fig. 6, a plan view of the engine with one cylinder and piston and part of the frame, in horizontal section, Fig. 7, a transverse vertical sectional view on the broken line 7—7 of Fig. 6, showing

the exhaust ports and the intake, and, Fig. 8, 55 a detail view in perspective of one of the wearing plates of the cross head.

Like reference characters mark the same parts wherever they occur in a plurality of the figures of the drawing. 60

Referring specifically to the drawings, 10 indicates the base or frame of the engine upon which are mounted, in alinement with each other, two cylinders 11 and 12, which are duplicates of each other and in each of 65 which is mounted to reciprocate a piston 13, only the piston in the right hand cylinder 12 being shown in detail, in section, in Figs. 1 and 6, it being deemed unnecessary to illustrate the other piston in cylinder 11 for the 70 reason that these pistons, like the cylinders, are duplicates of each other.

The two pistons are secured upon the opposite ends of a single piston rod 14, which latter passes through and is suitably secured 75 by bolts 16 in a cross-head 15 mounted to reciprocate between angle-iron guides 17, adjustably secured to a frame 18 which latter is held between the inner ends of the cylinders 11 and 12 by means of bolts 19, 80 the guides being adjustable on the frame 18 to take up wear, by means of bolts 20 passing through slots 21, and provided with suitable lubricating devices 22.

At the ends of the cross head 15 are trunnions 23 upon which are mounted the inner ends 24 and 25, of pitmen or connecting rods 26 and 27, and held by bolts 48 and 49, the outer ends 28 and 29, being mounted on wrist-pins 30 of fly-wheels 31 and 32, secured 90 at the opposite ends of the main shaft 33 duly journaled in bearings 35 and 36 on the engine base and provided with lubricating ports 37, said shaft 34 carrying a gear wheel 38 between the bearings 35 and 36 and the 95 ends of the pitmen 26 and 27 being provided with suitable lubricating openings 39 and 40.

The manner of mounting the pitmen upon the wrist pins of the fly wheels is shown in detail in Figs. 1 and 5 in which is shown a 100 split bushing 41 preferably made of bronze, mounted on each wrist pin with the split 42 at the top around which bushing is the split clamp 43 with its opening 44 on the opposite side of the wrist pin from that of the bronze 105 split bushing, whereby, when the clamp is tightened by the bolt 45 to take up wear, the bushing will remain cylindrical in form.

Washers 46 at the ends of the trunnions of the cross head 15 and similar washers 47 at the ends of the wrist pins 30, are held in their positions by means of bolts 48 and 49 threaded through said washers and respectively into said trunnions and wrist pins.

The cylinders are provided with water jackets 50 into which water enters through an inlet port 51 and after circulating entirely around and throughout the length of the cylinders, said water passes out of an outlet port 52 and is carried off through any suitable pipes, (not shown).

Each of the cylinders comprises an inner head 53, there being provided therein a suitable packing as at 54 held in place by a threaded sleeve 55, said head 53 being secured to the inner end 56 of the cylinder by bolts 57, said inner end also being secured by bolts 19 to the frame 18 as before described.

The outer head 58 of each cylinder is partly cylindrical and is secured to the main body of the cylinder by bolts 59, said outer end forming the explosion chamber 60 into which opens a valve 61, self-closed outwardly, by a spring 62 coiled around the valve stem 63 and secured thereto at 64 having its inward bearing against a spider 65 in the valve casing 66, through which spider the valve stem may reciprocate in opening and closing.

The valve casing 66 projects downwardly from the cylinder, into the primary gas chamber 67, its lower end in said chamber being open, and said chamber extending horizontally, the length of the cylinder and being provided with a port 68 at its inner end, opening into the inner end of the cylinder. Projecting outwardly from the inner end of the primary gas chamber 67 is another valve casing 69 in which operates a valve 70 self-closed outwardly by a spring 71, the valve casing 69 communicating with one end 72 of a manifold 73 which at its center communicates with a carburetor 74 of any approved construction, the opposite end of the manifold, as at 75 in Fig. 4, communicating with the cylinder 11.

At a point within the cylinders, as at 76 in Figs. 1 and 6, a series of exhaust openings or ports 76 are provided, extending entirely around the cylinder and all communicating with a manifold 77 extending entirely around the cylinder, its open upper ends forming an exhaust port to the outer air as at 78, Fig. 7. These ports 76 are so located as to be closed by the pistons and to be opened when said pistons have nearly reached the ends of their inward strokes.

The pistons are provided with suitable packing rings 79 and the inner ends of the pistons are cylindrical, and the piston rod at its outer ends passes into solid portions of the pistons, being suitably secured therein,

their extreme outer ends being preferably conical and extending into spaces 80 between said solid portions and the outer heads 81.

On the main shaft, alongside of the transmission gear 38, is the time ring 82 provided with a handle 83 and contact points 84, 85, while a spring 86 on the contiguous side of the gear 38 carries a roller 87, which is maintained by the spring in position to contact with said contact points at suitable set times in the rotation of the shaft, the timer being held against rotation in the usual manner, and the circuit being closed to make a spark to cause an explosion in one of the explosion chambers each time contact between the roller and contact point occurs.

Any approved batteries and circuit may be employed, it being deemed unnecessary to illustrate an example herein.

From the foregoing it will be apparent that all of the objects of the invention are carried out in the described construction.

The construction is strong, simple and economical. When the pistons are moved to the right, the gas in the right hand end of the right hand cylinder forms a cushion at the end of the stroke and vice versa, when the pistons are moved to the left, the gas in the left hand end of the left hand cylinder forms a cushion at the end of that stroke.

All of the parts needing adjustment from time to time are so constructed and located that they are readily accessible from the outside, thus avoiding the necessity of crawling under or climbing over parts during such adjustments.

The exhaust ports extend evenly all around the cylinders thereby keeping them in proper alignment for the work, and the provision of an inlet well in each cylinder head avoids the waste of gases usual in two-cycle engines.

The primary gas chambers are formed integral with the cylinders whereby the heat of the cylinders is communicated to the gases, thereby assuring more perfect combustion.

I have described the construction, arrangement and combination of the several parts comprised in my invention very specifically but I wish it to be understood that I do not confine my invention thereto, as many slight changes and variations might suggest themselves to the skilled mechanic within the spirit and scope of my invention as herein-after claimed.

Having thus fully described my invention what I claim as new and desire to secure by Letters Patent of the United States, is:

1. An internal combustion engine comprising a pair of aligned cylinders, a frame between said cylinders to which they are secured, adjustable angle iron guide plates or

said frame, a cross head slidably mounted between said guide plates, a piston rod centrally connected to said cross head and extending into each cylinder, and a piston head 5 in each cylinder connected to the contiguous end of the piston rod.

2. An internal combustion engine comprising a pair of alined cylinders, a frame between said cylinders to which they are set 10 cured, adjustable angle iron guide plates on said frame, a cross head slidably mounted between said guide plates, a piston rod centrally connected to said cross head and extending into each cylinder, and a piston

head in each cylinder connected to the contiguous end of the piston rod, said frame being of skeleton formation and the piston rod being provided with compressible packing and with compressing means accessible through openings in said skeleton frame. 15 20

In testimony whereof I have signed my name to this specification in the presence of two subscribing witnesses.

ANTON I. SANDBO.

Witnesses:

JULIUS BERG,
W.M. A. SHINE.
